UNITED STATES PATENT OFFICE.

WILLIAM C. REYNOLDS, OF COLLIERSTOWN, VIRGINIA.

IMPROVEMENT IN SEED-PLANTERS.

Specification forming part of Letters Patent No. 158,440, dated January 5, 1875; application filed August 15, 1874.

To all whom it may concern:

Be it known that I, WILLIAM C. REYNOLDS, of Collierstown, in the county of Rockbridge and State of Virginia, have invented a new and Improved Seed-Planter; and I do hereby declare that the following is a full, clear, and exact description of the same, reference being had to the accompanying drawings, forming a part of this specification, in which—

Figure 1 is a vertical section; Fig. 2, a top view. Fig. 3 represents the changeable gage detached. Fig. 4 is a top view of the false bottom of the seed-box detached.

The invention will first be fully described, and then pointed out in the claim.

A is a short plow; B, the beam; C C, the handles, and D D the standards, to the ends of which shovels E E are attached. F is the central seed-furrow standard, having a shovel, G, directly back of which is the dropping-tube H. I is the seed-box, arranged at the back end of the double beam B. J is the slide, to which is attached a changeable seed-gage, K, hav-

ing a semicircular notch in rear end, so that, by placing end notched under the head of screw K', and giving the latter a turn, it is fastened, and, with the same facility, may be removed without ever taking out the screw. The end of this gage also works under the spring L, which prevents clogging of the seed. P is a detachable false bottom in the seed-box, which relieves the slide J from the weight of the seed by subjacent supports and side apertures p p. The pressure over the seed-vent of slide is thus removed, and its liability to clog obviated.

Having thus described my invention, what I claim as new, and desire to secure by Letters Patent, is—

A false bottom, P, for seeder-hoppers, provided with subjacent support and side apertures, as and for the purpose specified.

WILLIAM C. REYNOLDS.
